B. G. H. & G. M. HATHAWAY.

Harvester.

No. 65,219.

Patented May 28, 1867.

United States Patent Office.

BRADFORD G. H. HATHAWAY AND GEORGE M. HATHAWAY, OF ROCK STREAM, NEW YORK.

Letters Patent No. 65,219, dated May 28, 1867.

IMPROVEMENT IN HARVESTERS.

The Schedule referred to in these Letters Patent and making part of the same.

TO ALL WHOM IT MAY CONCERN:

Be it known that we, BRADFORD G. H. HATHAWAY and GEORGE M. HATHAWAY, of Rock Stream, in the county of Yates, and State of New York, have invented a new and useful Improvement in Harvesters; and we do hereby declare that the following is a full, clear, and exact description of the construction and operation of the same, reference being had to the annexed drawings making part of this specification, in which—

Figure 1 is a perspective view.

Figure 2 is a side elevation showing the connection of the cutting mechanism with the main frame as seen from the wheel side.

Figure 3 is a side elevation showing the arrangement of the planet-wheels on the driving-wheel.

Figure 4 is an elevation of the opposite side of the box setting against the driving-wheel and enclosing the working gearing.

Figure 5 is an elevation of the ratchet-wheel.

Figure 6 is an elevation showing the inside of the case covering the gearing, with the plate shown in fig. 4 removed.

Figure 7 is an elevation of the last referred to plate.

Figure 8 is a transverse section of the wheel-cap and gearing.

Figure 9 is a perspective view of part of the working mechanism.

The nature of our improvements will fully appear from the following description and claims. We will so describe the mechanism that a person skilled in the art would be enabled to construct the same.

This machine is a single driving-wheeled harvester, convertible into either a reaper or mower. We shall describe, as we have represented in the drawings, the machine as prepared for reaping. It has no frame such as is commonly found in harvesters, the whole gearing being closely encased and attached to the casing, as we will more fully hereinafter describe.

The tongue A is attached to the rigid axle B so as to be balanced by the weight of the driver riding upon the seat, as the standard S supporting the seat is attached to the hind end of the tongue. C is the driving-wheel running upon the ground, having spurs across its face in the usual manner. This wheel turns freely upon the axle B upon a pipe-formed hub. This wheel is cast either solid, as shown, or with arms properly placed to sustain the planet-wheels D. These latter wheels are spur-wheels of the same size, the centres of which are in the circumference of a circle, of which the centre is the centre of the axle B, and in the angles of an equilateral triangle. They turn upon axles formed as wrist-pins upon the inner face of the solid centre or radial arms of the ground-wheel C. The planet-wheels D communicate motion to the pinion E, which turns freely about the shaft B on the pipe-formed bearing of the wheel G, which will be hereafter described. The inner side of the hub of the pinion projects slightly from the ends of the cogs to sustain the detent E' resting upon a spring, by which it is forced against the serrated ratchets on the inner face of the cup-formed wheel F, so that the latter wheel shall be driven forward by the forward motion of the ground-wheel, and when the latter is moving backward the pawl shall revolve within the wheel F and not communicate motion to the same. H is a hollow hemisphere fastened rigidly to the axle B. It has near its edge a projecting flange, H', which fits within the cup-formed side or inner face of the ground-wheel C, and on its inner face is provided with a gearing corresponding in pitch with the planet-wheels D, which mesh into and are impelled by it, as the wheel to which they are attached revolves forward or backward. G is a bevel-wheel turning on a pipe-formed bearing on the axle B. This wheel fits snugly but so as not to touch within the case H inside of the gearing H', and the gearing on its inner face matches into and communicates motion to the bevelled pinion K, which turns within a projection, H'', as seen from the outside, on the case H fitted to receive them. The wheel G is driven by the ratchet-wheel F only when the ground-wheel C is revolving forward, as explained. In order to subject the knives to the will of the driver, we form the ratchet-wheel F with holes, and also the wheel G with holes G''. Between the wheel G and the casing H we place, on the shaft, the loose collar I formed with a groove cut around its middle. From the edge of the collar project the pins I'. When these pins pass through the face-plate G and ratchet-wheel F, they will be revolved by the forward motion of the wheel C; but when retracted from the latter it will turn without

moving the wheel G and the mechanism connecting it with the knives. This operation is effected by the semi-circular yoke I'', rod I''', and lever I⁴, on the outside. The shaft K passes through the casing, and, by the crank-wheel K' and pitman L, drives the knives M. The platform rests upon the grain-wheel N' and wheel N attached to the shoe M'. The grain side of the axle is supported upon a triangular frame, O, from an arm, O', of which the rear of the platform is supported. An L-formed piece, Q, is pivoted to the front of the frame O, and through a slot in the leg of the L passes the wrist-pin Q''. The wheel R runs upon the ground. A lever, P, turning on the axle B, which passes through an eye formed in it, has underneath the axle a curved toe, P', which passes through the stirrup Q', which unites it to the piece Q. The toe P' is curved eccentrically, and by the motion of the lever the triangular frame O is raised or lowered at will, thus regulating the height of the cut. A dog, P², holds the lever P in position. T is a brace extended from the case H to the shoe, and sustaining also the tongue, by which the entire machine is held rigidly in place.

What we claim, and desire to secure by Letters Patent, is—

1. The ground-wheel C, in combination with the planet-wheels D pivoted to its inner face, and a fixed gearing, H', communicating motion to a pinion, E, so arranged in combination with a detent that it can revolve only with the forward motion of the ground-wheel, substantially as described.
2. The combination of the planet-wheels D, pinion E, detent E', and ratchet-wheel F, when said parts are respectively constructed and arranged substantially as set forth.
3. The hemispherical case H when constructed with internal gearing H', and having a collar by which it is attached to a rigid axle, so as to dispense with a frame, substantially as set forth.
4. The combination of the ratchet-wheel F, bevel G, and collar I with its pins I', yoke I'', rod I''', and lever I''', substantially as and for the purpose set forth.
5. The arrangement of the case H, axle B, tongue A, brace T, shoe M', and frame O, substantially as set forth.
6. The combination of the wheel R, arm Q, frame O, and lever P, said parts being respectively constructed and arranged as and for the purpose set forth.

In testimony whereof we have signed our names to this specification in the presence of two subscribing witnesses.

B. G. H. HATHAWAY,

GEO. M. HATHAWAY.
